Inventor:
Cromwell A. B. Halvorson, Jr.

by *Albert G. Davis*

His Attorney,

UNITED STATES PATENT OFFICE.

CROMWELL A. B. HALVORSON, JR., OF LYNN, MASSACHUSETTS, ASSIGNOR TO GENERAL ELECTRIC COMPANY, A CORPORATION OF NEW YORK.

LIGHTING UNIT.

1,400,817.

Specification of Letters Patent. Patented Dec. 20, 1921.

Application filed March 12, 1921. Serial No. 451,665.

To all whom it may concern:

Be it known that I, CROMWELL A. B. HALVORSON, Jr., a citizen of the United States, residing at Lynn, in the county of Essex, 5 State of Massachusetts, have invented certain new and useful Improvements in Lighting Units, of which the following is a specification.

My invention has reference to lighting 10 units. More specifically it relates to units for street and other outdoor illumination in which case a wide downward spread of light is desired.

An object of my invention is to provide 15 a simple and efficient lighting unit of this character in which a single member forms a high voltage insulator, a lamp housing and support, and a reflector, thereby eliminating numerous elements heretofore employed, and greatly simplifying its construction.

Another object of my invention is to provide a rugged lighting unit, which is not easily broken, nor subject to windage, and 25 which may withstand the elements.

My invention will be better understood from the following description taken in connection with the accompanying drawings and its scope will be pointed out in the appended claims.

In the accompanying drawings, Figure 1 is a perspective view of one type of lamp 35 unit embodying my invention; Fig. 2 is a central vertical sectional view of the same unit; and Fig. 3 is a modified detail of Fig. 2.

Referring to the drawings, in which the numeral 1 indicates a body of insulating material, preferably porcelain, which is 40 especially desirable on account of its non-flexible and weather-proof qualities. This body is substantially a bell-shaped structure, having a central chamber 2, which diminishes in size in the neck 3 of the 45 body. The neck 3 is formed with an internal annular flange 4 integral with the body 1, which supports electrical terminals 5, 5, of suitable conducting material. These terminals are secured to the flange 4 by screws 50 6, 6. Contact blades 7, 7, are in electrical engagement with the terminals 5, 5, and are bent upwardly over the flange 4. These blades are normally urged inwardly by springs 8, 8. The pair of blades 7, 7, and 55 springs 8, 8, extend between the terminals

5, 5, and the flange 4, and are also secured in position by the screws 6, 6. The wall of the body 1 is provided with openings 9, 9, through which the line conductors 10, 10, pass. These conductors are electrically secured in suitable holes 11, 11 in the terminals 5, 5, by screws 12, 12. The body 1 is preferably provided with tie ears 13, 13, integral therewith for the conductors 10, 10. In another form of my invention the 60 openings 9 may be placed near the flange 4 and the terminals 5 may be prolonged to extend through the openings so that the conductors may be secured externally of the body 10, as shown in Fig. 3. 70

A light source 14, which may be any suitable type of incandescent lamp, is supported in a socket 15 having spring terminals 16, 16, arranged to coact with the contact blades 7, 7, in a manner readily understood. In 75 one type of unit embodying my invention, a portion of the inner surface of the chamber 2, for example, the surface below the socket 15, indicated by the line 17 is preferably glazed and therefore reflecting. It may also 80 be of suitable curvature to direct reflected rays in a general downward and moderate lateral direction. At its lower edge, that portion of the body 1 forming a wall around the chamber 2 gradually thickens and extends outwardly rather abruptly, as shown 85 in the drawings. The lower surface of this wall, which is the edge of the bell, is formed with a number of radially waved reflecting surfaces 18, substantially perpendicular to 90 the axis of the body 1 and concentric with the chamber 2. These reflecting surfaces are located slightly above the light source, which I have indicated as a point source at 95 19, for purposes of illustration. In accordance with well-known laws of reflection, rays of light striking the surface 18, are given a wide lateral spread in a general downward direction.

The complete unit thus described is supported by a suitable hood 20, which may be of cast iron, to which it is secured by screws 21. The upper portion of the hood is formed with a neck 22, which may be threaded or provided with other suitable means for securing it to a standard. 100

While I have described my invention as embodied in concrete form in accordance with the provisions of the patent statutes, it should be understood that I do not limit 110

my invention thereto, since various modifications thereof will suggest themselves to those skilled in the art without departing from the spirit of my invention, the scope 5 of which is set forth in the annexed claims.

What I claim as new and desire to secure by Letters Patent of the United States, is:—

1. A light fixture comprising a light source, a body of insulating material formed 10 with a bell shaped, open mouthed central chamber in which the light source is located, and a reflecting surface formed on said body at the edge of said chamber and located slightly above the light source 15 whereby the rays reflected receive a wide downward spread.

2. A light fixture comprising a light source, a body of insulating material formed with a bell shaped, open mouthed central 20 chamber in which the light source is located, and a reflecting surface, having radial waves, formed on said body at the edge of said chamber, extending laterally substantially 25 perpendicular to the axis of said body and located slightly above the light source whereby the rays reflected by the waves receive a wide downward spread.

3. A light fixture comprising a light source, a body of insulating material formed 30 with a central chamber in which the light source is located, and a reflecting surface formed on said body at the edge of said chamber, electric terminals carried by said body, and a removable socket for supporting the slight source slightly below said reflecting surface.

4. A light fixture comprising a light source, a body of insulating material formed

with a bell shaped, open mouthed central chamber having a downwardly reflecting 40 inner surface in which the light source is located, and a reflecting surface having radial waves formed on said body at the edge of said chamber extending laterally substantially perpendicular to the axis of said body 45 and located slightly above the light source, whereby the rays reflected by the waves receive a wide downward spread.

5. A light fixture comprising a light source, a body of insulating material formed 50 with a laterally and downwardly reflecting surface, and with a central chamber having a downwardly reflecting inner surface, said chamber housing the light source, electric terminals within said body, electric conductors to said terminals extending through openings in the wall of said body, and a removable socket for the light source for connection with the terminals.

6. A light fixture comprising a body of 60 insulating material having a central chamber with a downwardly reflecting inner surface, a radially waved reflector on its lower edge concentric with said chamber, electric terminals within the chamber, electric conductors extending through the wall of the chamber to said terminals, tie ears for the conductors integral with said body, a source of light and a socket supporting the same 65 adapted to be inserted within and removed 70 from chamber with the light source slightly below the radially waved reflecting surface.

In witness whereof, I have hereunto set my hand this 9th day of March, 1921.

CROMWELL A. B. HALVORSON, JR.
